Ch. Farren Attorney

UNITED STATES PATENT OFFICE.

JOHN M. BIGGS, OF HELENA, ARKANSAS.

ATTACHMENT FOR FURNITURE.

Application filed October 31, 1921. Serial No. 511,875.

To all whom it may concern:

Be it known that I, JOHN M. BIGGS, a citizen of the United States, residing at Helena, in the county of Phillips and State 5 of Arkansas, have invented certain new and useful Improvements in Attachments for Furniture, of which the following is a specification.

This invention relates to attachments for 10 furniture, and more particularly to devices to be applied to the legs of furniture to prevent insects from crawling thereon.

An object of the invention is to provide a 15 simple attachment in the form of a cup adapted to be arranged on the lower end of the leg of the furniture to contain an insecticide and thus prevent the insects from reaching the legs of the furniture.

A further object of the invention is the 20 provision of an attachment which can be simply and cheaply manufactured.

In the accompanying drawings, I have shown one embodiment of the invention. In this showing:

25 Figure 1 is a side elevation of the lower portion of the leg of an article of furniture, showing the invention applied.

Figure 2 is a central vertical sectional view, and,

30 Figure 3 is a detail view of the attachment removed.

Referring to the drawings, the reference numeral 1 designates the leg of a table, chair, bed, desk, or other article of furniture. As 35 shown, it may be provided with suitable ornamentation 2.

The device forming the subject matter of the present invention comprises a substantially semi-spherical cup 3, formed of metal 40 or other suitable material provided with a central opening. A fastening member 4 is adapted to be secured to the bottom of the cup within the opening, and extend upwardly therefrom. The fastening member is 45 provided with a reduced end 5, adapted to be received in the opening. It may be further welded or soldered to the cup to prevent leaking. A washer 7 is arranged on a shoul-

der 8 formed on the fastening element. The upper end of the fastening element is reduced and threaded, as at 9, and is adapted to be received in a threaded opening in the leg of the furniture.

In operation, the device is attached to the leg of an article of furniture, and a suitable material, such as oil mixed with creosote, is arranged in the cup 3. Ants, and other insects attempting to reach the leg of the furniture and crawl upwardly on to the article of furniture, are prevented from doing so, as the leg is spaced from the floor and it is necessary for them to pass through the mixture of oil and creosote or other material to reach the bottom of the leg.

It is to be understood that the form of 65 my invention herewith shown and described is to be taken as a preferred example of the same, and that various changes in the shape, size, and arrangement of parts may be resorted to without departing from the spirit 70 of the invention or the scope of the subjoined claim.

Having thus described my invention, I claim:

A guard for furniture legs comprising a 75 cup having a smooth substantially semi-spherical outer surface and being provided in its lowermost portion with a vertical opening, and a vertical fastening member 80 having a reduced lower end mounted in said opening and adapted to be secured therein and form a closure therefor whereby said cup is adapted to contain a liquid, the upper end of said fastening member being threaded 85 for reception in an opening in the furniture leg, the lower end of said fastening member being smooth and forming a continuation of the semi-spherical outer surface of 90 said cup and adapted to directly support the weight of the furniture.

In testimony whereof I affix my signature in presence of two witnesses.

JOHN M. BIGGS.

Witnesses:

GEO. A. BROMLEY,

L. J. BARRETT.
